SWIMMING POOL

Alex Gersh, 20 Dietz Court, Kingston, N.Y. 12401, and
Ted H. Gersh, 30 Edgar St., Poughkeepsie, N.Y. 12603

Filed Aug. 1, 1966, Ser. No. 3,295

Term of patent 14 years

(Cl. D13—1)

FIG. 1

FIG. 2

FIGURE 1 is a perspective view illustrating a swimming pool showing our new design; and

FIGURE 2 is a sectional view, with one flange broken away, taken on the line 2—2 of FIGURE 1 showing the design of the walk platform, water trough, curved wall-trough-platform support, flange, and diving area.

We claim:

The ornamental design for a swimming pool, as shown and described.
